United States Patent Office

Des. 185,299

Patented May 26, 1959

185,299

WHEEL DOLLY OR SIMILAR ARTICLE

Stewart S. McClelland, Los Angeles, Calif., assignor to
Salsbury Corporation, Los Angeles, Calif., a corpora-
tion of California

Application April 21, 1958, Serial No. 50,549

Term of patent 14 years

(Cl. D14—3)

Fig. 1.

Fig. 3.

Fig. 4.

Fig. 2.

Fig. 1 is a perspective view of a wheel dolly showing my new design;

Fig. 2 is a side view;

Fig. 3 is a top view; and

Fig. 4 is a rear view thereof.

The essential features of my design reside in those portions shown in full lines.

I claim:

The ornamental design for a wheel dolly or similar article, substantially as shown and described.
